UNITED STATES PATENT OFFICE.

CHARLES E. SWANSON AND FRANK C. BURTON, OF CHICAGO, ILLINOIS, ASSIGNEES TO CHENEY TALKING MACHINE CO., OF CHICAGO, ILLINOIS, A CORPORATION OF ILLINOIS.

DESIGN FOR A PHONOGRAPH CABINET.

Application filed June 8, 1922. Serial No. 2,573. Term of patent 3½ years.

To all whom it may concern:

Be it known that we, CHARLES E. SWANSON and FRANK C. BURTON, citizens of the United States, residing in Chicago, in the county of Cook and State of Illinois, have invented a new, original, and ornamental Design for Phonograph Cabinets, of which the following is a specification.

In the accompanying drawing, forming part of this specification—

The single figure shows a perspective view of a phonograph cabinet embodying our invention.

We claim:

The ornamental design for a phonograph cabinet as shown.

CHARLES E. SWANSON.
FRANK C. BURTON.
